(57) **CLAIM**

The ornamental design for a cooler with partially detachable legs, as shown and described.

DESCRIPTION

FIG. 1 is an upper perspective view of the cooler with partially detachable legs showing my design.

FIG. 2 is a front view thereof;

FIG. 3 is a back view thereof;

FIG. 4 is a side view thereof;

FIG. 5 is an opposite side view thereof;

FIG. 6 is top view thereof;

FIG. 7 is a bottom view thereof;

FIG. 8 is another perspective view thereof, showing the lid in an open position; and,

FIG. 9 is an exploded perspective view thereof, showing the legs in a detached position.

The broken lines in FIG. 9 are presented for illustrative purposes only and for no part of the claimed design.
